US0D1102916S

(12) **United States Design Patent** (10) **Patent No.:** **US D1,102,916 S**
(45) **Date of Patent:** **** Nov. 25, 2025**

(54) **TIME MANAGER**

(71) Applicant: **Dongguan Shuangjun Electronics Co., Ltd.**, Dongguan (CN)

(72) Inventor: **Xiujun Yang**, Dongguan (CN)

(73) Assignee: **Dongguan Shuangjun Electronics Co., Ltd.**, Dongguan (CN)

(**) Term: **15 Years**

(21) Appl. No.: **29/922,750**

(22) Filed: **Dec. 26, 2023**

(51) LOC (15) Cl. **10-01**

(52) U.S. Cl.

USPC **D10/15**

Primary Examiner — Samantha Wood

(57) **CLAIM**

The ornamental design for a time manager, as shown and described.

DESCRIPTION

FIG. 1 is a front, right and top perspective view of a time manager showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the time manager that form no part of the claimed design.

1 Claim, 8 Drawing Sheets
